UNITED STATES PATENT OFFICE.

JAMES ALEXANDER SORRELLS, OF GAINESVILLE, GEORGIA.

BRAKE MECHANISM FOR LOOMS.

Application filed January 16, 1922. Serial No. 529,630.

To all whom it may concern:

Be it known that I, JAMES A. SORRELLS, a citizen of the United States, residing at Gainesville, in the county of Hall and State of Georgia, have invented a new and useful Brake Mechanism for Looms, of which the following is a specification.

This invention aims to provide an improvement in brake mechanisms for looms, 10 a general statement which can be qualified and explained in detail, only after sundry parts of a known loom construction have been explained, the improvement embodying a minute but exceedingly important 15 structural alteration in a standard loom brake.

Figure 1 shows in side elevation, a portion of a loom whereunto the device forming the subject matter of this application has been 20 applied; Figure 2 is a top plan of the structure shown in Figure 1; Figure 3 is an enlarged elevation showing a portion of the brake mechanism; Figure 4 is a section on the line 4—4 of Figure 3 and showing the 25 part wherein the improvement is specifically claimed to be located; Figure 5 is a perspective showing the improved form of hand lever for the brake mechanism.

The device forming the subject matter of 30 this application is an improvement in the well known Draper loom, one form of which is shown in patent No. 848,815, granted on April 2, 1907. The drawing shows a part of the loom disclosed in the aforesaid patent, 35 the frame appearing at 1, and a driving shaft 3 being journaled in the frame and carrying a fly wheel 6 adapted to be engaged by a brake shoe 7 mounted pivotally at 8 on the frame and connected to a first 40 rod or link 25 having a head 26 engaged by the short arm 27 of a lever 60, fulcrumed at 28 on the frame 1 and including a long arm 29 whereon a weight W is supported. A second link 36 passes slidably through 45 the arm 29 of the lever 60 and is provided at its lower end with a head 37 adapted to cooperate with the arm 29. A pivot element 50 unites the upper end of the link 36 with a bell crank lever 34, fulcrumed at 50 51 on a slotted holding plate 22 or other member of the loom frame. The bell crank lever 34 has a long arm 53 which rests against a stop 52, the stop being located in various places, the stop, in the form under 55 discussion, being on the link 36.

The structure as thus far described may

be considered to be old. In carrying out the invention, the bell crank lever 34 is provided with parallel fingers 55 having openings 54 wherein the pivot element 50 is mounted securely, preferably by riveting its ends on the fingers 55, as shown in Figure 4.

In the known and standard construction, the bell crank lever 34 has but one of the fingers 55, the pivot element being mounted in 65 the said finger, and the upper end of the link 36 being retained on the pivot element by the part 22 of the frame. In the standard construction, the upper end of the link 36 bears against the plate 22 directly, the 70 innermost finger 55 of Figure 4 being omitted, and the link being held on the pin, corresponding to the element 50, merely by contact with the part 22 of the loom frame. The upper end of the link 36 wears away 75 the part 22 of the loom frame, the pivot element becomes worn, and the link drops off the pivot element. In the device forming the subject matter of this application, the link 36 is held away from the part 22 of 80 the loom frame, by the innermost finger 55, and the pivot element 50 is riveted securely in both of the fingers 55, so that it cannot become loose.

I claim:—

In a loom, a frame; a driving shaft journaled on the frame; a brake shoe mounted movably on the frame and controlling the rotation of the shaft; a first link connected with the brake shoe; a first lever engaged 90 with the link; a second link slidable in the first lever and provided with a head adapted to cooperate with the first lever; a bell crank lever fulcrumed on a part of the frame; and a pivot element mounted in the 95 second link, the bell crank lever comprising two fingers, between which the second link extends, the provision of two fingers permitting the pivot element to be riveted at both ends, and the pivot element being so riveted, thereby to hold the pivot element securely in place, one of the fingers being interposed between the second link and the frame, to prevent a wearing of the frame by the link.

In testimony that I claim the foregoing as my own, I have hereto affixed my signature in the presence of two witnesses.

JAMES ALEXANDER SORRELLS.
